United States Patent Office.

RICHARD BUSH, OF SOUTH BROOKLYN, NEW YORK.

Letters Patent No. 67,408, dated August 6, 1867.

IMPROVED SOAP-HOLDER.

The Schedule referred to in these Letters Patent and making part of the same.

Be it known that I, RICHARD BUSH, of South Brooklyn, in the county of Kings, and State of New York, have invented a new and useful Soap-Holder; and I do hereby declare that the following is a full, clear, and exact description thereof, reference being had to the annexed drawings, making a part of this specification, in which—

Figure 1 is a front view of the device when shut.

Figure 2 is a vertical section down through the middle, and

Figure 3 is the bottom piece.

Fig. 2 shows most of the parts, to wit, the back A, which may be of wood or other material; the box B, open at the top and fastened to the back, as represented at F, or in an equivalent mode, the lump of soap resting inside, as indicated in red. D is the finger-piece to operate the bottom, and E the spring spiral bottom and arm, pressing against the bottom; and fig. 3 the revolving bottom, with its axis G and holes H. The parts may be made of any suitable materials; and may slightly vary in form without varying the essential nature and construction of the device.

The nature of the invention consists in a simple soap-holder that will let the soap dry, and let it conveniently fall into the hand by revolving the bottom. The construction and operation of the device are both so simple as to need no further description to enable those skilled in the art to make and use the same.

What I claim as my invention, and desire to secure by Letters Patent, are—

1. The soap-holder, with the revolving bottom, substantially in the manner and for the purpose set forth.
2. The whole device as an article of manufacture, when constructed substantially in the manner and for the purposes set forth and described.

RICHARD BUSH.
